UNITED STATES PATENT OFFICE.

HARVEY W. CUTSHALL, OF CHICAGO, ILLINOIS, ASSIGNOR TO MUDGE & COMPANY, OF CHICAGO, ILLINOIS, A CORPORATION OF ILLINOIS.

REVERSIBLE CYLINDER.

Application filed October 21, 1922. Serial No. 595,911.

To all whom it may concern:

Be it known that I, HARVEY W. CUTSHALL, a citizen of the United States, residing at Chicago, in the county of Cook and State of Illinois, have invented certain new and useful Improvements in Reversible Cylinders, of which the following is a specification, reference being had to the accompanying drawings, and to the reference characters 10 marked thereon, which form a part of this specification.

This invention relates to improvements in cylinders for internal combustion engines and more particularly to that type of engines used on platform motor cars used largely for maintenance and inspection work on railways, although adapted for other uses.

Heretofore, in order to conform to the necessity of placing the cylinder on either the right or the left hand side of the drive crank, it has been the custom to make a right and a left hand set of patterns and to cast the cylinders, rights and lefts. This is not only expensive but it requires having on hand, in stock, a quantity of both right and left hand cylinders for purposes of repairs and renewals, together with right and left hand sets of tools, templets, &c., to finish the 30 cylinders for use.

The principal object of my invention is to obviate these objectionable features and expense and to produce a type of cylinder which is reversible, so that it may be used 35 upon either the right or left hand side of the drive crank.

Another object of the invention is to produce a cylinder having a duplex manifold, either half of which may be used as 40 required.

Still another feature of the invention is to provide means, such as a removable deflector cover, over the cylinder exhaust openings, whereby the exhaust may be deflected 45 in the desired direction.

These and other objects and advantages of the invention will become manifest as I proceed with my specification.

In that form in which I have chosen to 50 illustrate the invention in the accompanying drawings:

Figure 1 is a side elevation of a typical cylinder for an internal combustion engine, constructed in accordance with my invention.

Figure 2 is a transverse vertical sectional view, of the cylinder with a deflector plate attached, the section being taken in the plane of the dotted line 2—2 of Figure 1.

Figure 3 is a perspective view of the deflector cover, detached.

Figure 4 is a view similar to the section shown in Figure 2, and in the same plane, but showing the cylinder turned about its central longitudinal axis so as to be located 65 on the side of the drive crank-shaft opposite to the side shown in Figure 2.

Thus Figures 2 and 4 show the reversible character of the cylinder for right and left hand use as desired.

Referring to the drawings: A represents the cylinder as a whole, comprising the cylinder body 1 having the usual concentric externally located rings or fins 2, a crank case 3, and inlet and exhaust ports 4 and 5, 75 through the wall of the body 1. Surrounding the inlet ports is a gas chamber 6 provided with diametrically opposed screw threaded passageways 7, 8, through hub supports 9 and 10, cast integral with the body 1. To one of these hubs, say 9, a carburetor C is secured, the opening 8 of the hub 10 being closed by an ordinary screw plug D.

Upon the outside of the body 1, above and below the horizontal axis of the body 1, are two lugs 11 and 12 extending lengthwise of the body and outwardly therefrom. Each lug has a centrally located half round recess 13 in its outer edge. These lugs are located, as shown, above and below the exhaust ports 5.

In Figure 3, I have shown detached the cover and deflector plate designated, as a whole, by the letter B, and comprising a back wall 14, two side walls 15, 15, all connected at the top by the transversely arranged and downwardly projecting lug 16. At their lower portion, the walls 15 are joined by a relatively narrow, transverse front wall 17, the upper margin or edge of which is provided with a centrally located half-round recess 18. The lower margins of the back wall 14, side walls 15, 15, and front wall 17, define the exhaust opening 19 of the deflector B.

On the cylinder body 1 on each side of the exhaust ports 5 is an outstanding circumferential rib 20, which extends, however, only from the lug 11 to the lug 12. The outer edges of these ribs 20 are formed on 110

an arc concentric with the cylinder surface. The front margins, 21, 21, of the side walls 15 of the deflector, are shaped to conform to and rest upon the outer surface of the cylinder body 1. The two side walls 15, 15, are spaced apart a distance sufficient to nicely fit over and embrace the parallel ribs 20, 20, when the deflector is positioned upon the cylinder. Upon the inside of each of said 10 deflector side walls and at a proper distance from the margin 21 is a lug or shoulder 22 against which the outer edge of the ribs 20, 20, abut when the deflector is in place.

To hold the deflector in place, the hook or 15 projecting lug 16 is placed over one of the lugs, 11, 12, (say the lug 11), as shown in Fig. 2, and the deflector seated against the cylinder body. This will bring the lower edge of the lug 12 and the upper edge of 20 the deflector front wall 17 into proper contact, with their respective half-round recesses 13, 18, in register to form a round passageway for a fastening bolt 23. This bolt will have a head 24 and a retaining nut 25, which form shoulders to embrace the side faces of the lug 12 and front wall 17, and securely lock them together.

By this construction it will be clear that 5 the exhaust will pass through the ports 5 to 30 the interior of the deflector B, be deflected downwardly and out through the bottom opening 19.

When the cylinder A is reversed with 35 respect to the crank shaft, from the position shown in Fig. 2 to that shown in Fig. 4, the bolt 23 is unfastened and removed, the deflector being hung at its top over the lug 12, which is now on top, and the wall 17 bolted to the lug 11. It will be understood, of 40 course, that when so reversed, the carburetor C and the closure or plug D will also be reversed, from engagement with the lugs 9 and 10 to engagement with the lugs 10 and 9, respectively.

45 It will be understood, however, that the one part of the manifold will not always be closed by the plug D, as for instance, where two fuel supplies are desired, a second carburetor would be used instead of plugging one of the passageways 7 or 8.

I claim as my invention:

1. In a reversible engine cylinder having 55 a duplex manifold and exhaust ports opposite the manifold ports, a hollow, open bottom deflector member, means for removably engaging said deflector with the cylinder to cover the exhaust ports, and means for locking the deflector to the cylinder, said removable engaging means including interlocking 60 lugs on the cylinder and deflector.

2. In a reversible engine cylinder having a duplex manifold and exhaust ports opposite the manifold ports, a hollow, open bottom deflector member, means for removably engaging said deflector with the cylinder to 65 cover the exhaust ports, and means for locking the deflector to the cylinder, said locking means including complementally notched parts on the deflector and the cylinder, and a headed bolt.

3. In a reversible engine cylinder having a duplex manifold and exhaust ports opposite the manifold ports, a hollow, open bottom, removable and reversible deflector member adapted to cover either of the exhaust ports, 75 and means for locking the deflector to the cylinder, said removable, reversible and locking means including interlocking lugs on the cylinder and deflector.

4. A reversible engine cylinder provided 80 with a duplex manifold, a pair of circumferentially located ribs, one on either side of the exhaust ports, lugs extending longitudinally of the cylinder and joining the ends of 85 said ribs, in combination with a hollow, open bottom member adapted to surround said lugs and to cover the exhaust ports, and means for removably securing said member to the cylinder.

5. In an internal combustion engine, a 90 cylinder, exhaust port or ports through its wall, a pair of circumferentially extending ribs on the outside of the cylinder, one on each side of said exhaust port or ports, a pair of radially and longitudinally extending 95 lugs on the cylinder between said rib ends, one at each end of the exhaust port or ports, the outer face of each lug being centrally recessed, in combination with an open bottomed, removable deflector hood member, the 100 side walls of which have curved faces to fit upon the cylinder and to fit over said circumferential ribs, a downwardly projecting lug or hook member on said deflector adapted to fit over and engage one of the longitudinally 105 extending cylinder lugs, a front wall member on the deflector, one edge of which is adapted to engage the edge of the other cylinder lug and is provided with a recess complementary to the recess in said lug, and 110 a locking bolt in said registering recess.

In testimony that I claim the foregoing as my invention I affix my signature in the presence of two witnesses, this 12th day of October, 1922.

HARVEY W. CUTSHALL.
